ORNAMENTAL NOVELTY DEVICE

Sol H. Burger, Newark, N. J.

Application October 1, 1948, Serial No. 52,311

9 Claims. (Cl. 41—16.5)

1

This invention relates to decorative devices and more particularly to an improved ornamental novelty device to be attached to such objects as the handle-bars of bicycles and motor-cycles.

In my prior application Serial No. 779,239, filed October 11, 1947, there is disclosed and claimed a decorative device projecting from an aperture in the closed end of a bicycle handlebar grip and dependently supported by the latter, the decorative device comprising a plurality of flat, flexible streamers arranged in superimposed relationship with respect to each other and folded upon each other along a fold line intermediate their ends to form a bulge, the folded streamers extending from the bulge through and out of the aperture in the closed end of the grip, the portions of the streamers along and adjacent the bulge being embracingly supported by the wall of the grip.

It is among the objects of the invention to provide an improved ornamental device comprising a group of flexible elements or streamers attachable to a handle-bar hand grip of a bicycle or motor-cycle, which device is easy to attach to a hand grip and requires no important modification of the latter and does not interfere in any way with the normal use of the grip, and which is simple and durable in construction, economical to manufacture, and neat and attractive in appearance.

Other objects and advantages will become apparent from a consideration of the following description and the appended claims in conjunction with the accompanying drawing, wherein:

Figure 1 is a perspective view of an ornamental device illustrative of the invention;

Figure 2 is a longitudinal medial cross-section of a fragmentary portion of the device illustrated in Figure 1 showing the details of construction of the device;

Figure 3 is a longitudinal cross-section similar to Figure 2 but taken in a plane disposed substantially at right angles to the plane of the section of Figure 2 and is taken substantially on the line 3—3 of Figure 2;

Figure 4 is a view similar to Figure 2 but showing a somewhat modified form of fastening element for the device;

Figure 5 is a view similar to Figure 4 but taken on a plane along the line 5—5 of Figure 4 disposed substantially at right angles to the section plane of Figure 4;

Figure 6 is a view similar to Figures 2 and 4 but showing a still further modified form of fastening element; and

2

Figure 7 is a view similar to Figure 6 but taken in a plane substantially on the line 7—7 of Figure 6 perpendicular to the section plane of Figure 6.

5 With continued reference to the drawing, the numeral 10 designates the handle-bar of a motor-cycle or bicycle, a fragmentary end portion only of such handle-bar being shown for the purpose of the present disclosure.

10 A hollow rubber grip 11 receives the end portion of the handle-bar and is frictionally held thereon and a plurality of flexible elements in the form of long narrow streamers 12 are secured to the grip 11 by a fastener 13 over which the elements 12 are folded intermediate their length, the folded-over portions of the streamers and the adjacent portion of the fastener 13 being enclosed in an ornamental sleeve 14.

The grip 11 is in the form of an elongated hollow or tubular body, conventionally formed of rubber and has one end open to receive the corresponding end portion of the handle-bar 10 and its opposite end closed by an end wall 15, the grip near its closed end being spherically shaped or annularly beaded to provide an ornamental appearance.

20 In accordance with the present invention the end wall 15 of the grip is provided with a substantially central opening or aperture 16 smaller than the handle-bar receiving concavity 11 in the grip to provide around the opening 16 an internal radial shoulder 18.

The fastener 13 may be formed of metal wire or other suitable material and is generally U-shaped in form having a pair of substantially parallel legs 19 and a bight 20 extending between the legs at corresponding ends of the latter, the fastener being open at the opposite ends of the legs.

30 40 The ornamental elements or streamers 12 are pulled through the fastener adjacent the bight 20 so that they extend substantially equal distances to each side of the fastener and are folded over the bight of the fastener, as particularly illustrated in Figures 3, 5, and 7, in superposed relationship so that all of such elements are firmly secured to the fastener 13.

45 The legs 19 of the fastener are turned outwardly and recurved near the outer end of the fastener, as indicated at 21 in Figure 2, or may be turned outwardly without being recurved, as indicated at 22 in Figure 4, so that they extend outwardly substantially perpendicular to the remaining portions of the corresponding legs. In 50 both cases the legs of the clip of fastener 13

or 13' are inserted through the aperture 16 in the end wall 15 of the grip and then allowed to separate by the resiliency of the material of the fastener to overlie the internal shoulder 18 of the grip thereby firmly securing the fastener in the grip.

After the fastener has been allowed to expand in the grip the sleeve 14 is pushed forwardly to cover the folded-over portions of the streamers 12 and the portion of the fastener extending out of the grip beyond the outer surface of the end wall 15, as is clearly illustrated in Figures 2 and 3.

Sleeve 14 not only constitutes a cover for the fastener, but also rests against the adjacent end of the handle-bar grip to tighten the connection between the streamers and the grip and hold the streamers in place and, by closely surrounding the folded-over portions of the streamers, maintains the shape of the device and secures the streamers against removal from the fastener. It also adds a decorative factor to the ornamental device, as it may be given a color contrasting with the color of the streamers.

The fastener 13, as illustrated in Figures 2 and 3, has portions of its legs spaced from the bight 23 spaced somewhat more closely than the length of the bight to provide a necked-in portion receivable in the restricted aperture 16 in the end wall of the grip. In the form of fastener illustrated in Figures 4 and 5, the legs 23 are somewhat shorter than the legs of the fastener 13 of Figures 2 and 3 and extend substantially straight from the bight 24 to the upset end portions 22 so that the aperture 16' in the end wall of the grip is somewhat larger than the aperture 16 or is slightly elongated to receive the wider spacing of the fastener legs and thus effectively hold the fastener against rotation relative to the grip. As stated above, the upset end portions 22 are disposed substantially perpendicular to the corresponding legs and the legs are inwardly curved, as indicated at 25 at the inner ends of the upset portions 22 to avoid too sharp a bend in the legs.

In the form of the invention illustrated in Figures 6 and 7, the fastener 26 is in the form of a U-shaped staple having a transverse bight 27 and divergent legs 28 pointed at their outer ends.

In this arrangement the flexible elements or streamers 12 are folded, substantially at their middle length locations, about the bight 27 of the staple 26 with the legs of the staple extending along the streamers toward the ends of the latter. The streamers are inserted through the aperture 16 of the grip 11 and the staple 26 is disposed entirely within the grip with the pointed ends of its legs imbedded in the shoulder 18 of the grip and its bight 27 spaced from such shoulder. As the staple is being forced into the internal shoulder of the grip, the points of the staple are spread apart, so that, as the strips or streamers are pulled to force the staple into the shoulder, the pressure exerted by the folded-over portions of the streamers on the bight of the staple acts to pull the two pointed ends of the staple into the shoulder of the grip in diverging relationship to each other, thus providing a firm and secure connection between the streamers and the grip. In this case, it is not necessary to use the sleeve 14 as no portion of the fastener or staple 26 is exposed at the outside of the grip.

In each case the fastener provides an extremely convenient means for easily and firmly attaching the streamers to the grip so that the streamers cannot be accidentally separated from the grip and so that the streamers can be at-

tached to an existing grip by merely inserting the fastener through the end wall of the grip.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

15. An ornamental novelty device comprising a hollow body having an internal shoulder, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body.
20. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter.
25. An ornamental novelty device comprising a hollow body having an internal annular shoulder adjacent one end thereof, a U-shaped fastener having an intermediate bight and a pair of legs, and a plurality of superposed flexible elements folded intermediate their length about the bight of said fastener, said fastener having the end portions of its legs remote from said bight engaging the internal annular shoulder of said body at any selected rotational position relative to said body to attach said flexible elements to said body at said one end of the latter.
30. An ornamental novelty device comprising a hollow body having an internal shoulder adjacent one end thereof, a U-shaped fastener having an intermediate bight and a pair of legs, and a plurality of superposed flexible elements folded intermediate their length about the bight of said fastener, said fastener having the end portions of its legs remote from said bight engaging the internal shoulder of said hollow body to attach said flexible element to said body at said one end of the latter.
35. An ornamental novelty device comprising a hollow body having an internal shoulder adjacent one end thereof, a U-shaped fastener having an intermediate bight and a pair of legs, and a plurality of superposed flexible elements folded intermediate their length about the bight of said fastener, said fastener having the end portions of its legs remote from said bight engaging the internal shoulder of said hollow body to attach said flexible element to said body at said one end of the latter.
40. An ornamental novelty device comprising a hollow body having an internal shoulder adjacent one end thereof, a U-shaped fastener having an intermediate bight and a pair of legs, and a plurality of superposed flexible elements folded intermediate their length about the bight of said fastener, said fastener having the end portions of its legs remote from said bight engaging the internal shoulder of said hollow body to attach said flexible element to said body at said one end of the latter.
45. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter.
50. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter.
55. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter.
60. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter.
65. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter.
70. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter.

ends thereof remote from said bight overlying said internal shoulder to retain said fastener in said body.

6. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter, said fastener having intermediate portions of its legs extending through said hollow body from the exterior to the interior of the latter and portions at the ends of its legs remote from said bight extending substantially perpendicularly to the intermediate portions of said legs and overlying said internal shoulder.

7. An ornamental novelty device comprising a hollow body having an internal shoulder adjacent one end thereof, a U-shaped fastener having an intermediate bight and a pair of legs, and an elongated flexible element folded intermediate its length about the bight of said fastener, said fastener having the end portions of its legs remote from said bight engaging the internal shoulder of said hollow body to attach said flexible element to said body at said one end of the latter, said fastener being disposed entirely within said hollow body and having its legs pointed at the ends thereof remote from said bight and engaged in said internal shoulder.

8. An ornamental novelty device comprising a hollow body having an internal shoulder adjacent one end thereof, a U-shaped fastener having an intermediate bight and a pair of substantially parallel legs extending through said one end of said body and having portions of its legs at the ends thereof remote from said bight engaging

said internal shoulder to connect said fastener to said hollow body, the bight of said fastener being disposed outside of said body and spaced from said one end of the latter, foldable elements folded intermediate their length over the bight of said fastener, and an ornamental sleeve surrounding the folded-over portions of said elements and the portion of said fastener disposed outside said body.

9. An ornamental device comprising a hollow body having an internal shoulder adjacent one end thereof, a U-shaped fastener having an intermediate bight and a pair of substantially parallel legs extending through said one end of said body and having portions of its legs at the ends thereof remote from said bight engaging said internal shoulder to operatively connect said fastener to said hollow body, the bight of said fastener being disposed outside of said body and spaced from said one end of the latter, and foldable elements folded intermediate their length over the bight of said fastener.
